FACE MASK

Edwin E. Wood, Malden, and William A. Hafferty,
Charlestown, Mass.

Application September 12, 1952, Serial No. 309,202

6 Claims. (Cl. 128—141)

1

The present invention is an improvement in face masks, more particularly face masks for cold weather, and relates to the same subject matter which is described, disclosed and claimed in our copending application Serial No. 277,030, filed March 17, 1952.

One of the objects of the present invention is to provide a face mask of transparent plastic material which will not quite be on the inside and which will also serve as a means for protecting the face against temperatures encountered in cold weather.

Another purpose of the face mask is to permit normal breathing through the mask under comfortable conditions so that the air is to a great degree conditioned before it is inhaled by the user.

An additional purpose of the present invention is to provide a mask which is strong, durable, easily worn and which can be used out-doors in extreme northern latitudes and which will permit substantially normal action of the individual wearing it under very severe weather conditions.

Other advantages and improvements of the present invention will be more readily understood from the description given below in the specification when taken in connection with the drawings showing an embodiment thereof, in which:

Figure 1 shows an elevation of the face mask looking at the inside of the mask.

Figure 2 shows an elevation of the face mask looking at the outside of the mask that is opposite to the side shown in Figure 1.

Figure 3 is a cross section on the line 3—3 of Figure 1, and,

Figure 4 is a side elevation of Figure 2 as viewed from the right side of Figure 2.

The mask shown in the embodiment comprises a transparent outer wall 1 and a substantially parallel transparent inner wall 2 which curve around in substantial parallel relationship to form the front sides of the mask corresponding to the face of an individual. These two parallel walls 1 and 2 are separated by a substantially rigid plastic rim or flange 3 which extends all around the periphery of the walls 1 and 2 and which with the walls 1 and 2 form a hermetically sealed chamber around the whole shell of the face mask. The flange 3 may be made of any other suitable material, such as fiber wood or composition material. The space in the chamber between the walls 1 and 2 is preferably exhausted by means of a valve 4 of the usual construction well known in the art in the outer face of the mask. The air does not have to be completely exhausted but

5 a reduction in pressure to a few millimeters is desirable. The walls 1 and 2 are stiff enough and the separator 3 is sufficiently strong so that under no condition is the chamber in the mask collapsed. This is in part due to the fact that the faces of the chamber are curved such that the pressure against the surface is in different directions over different parts of the surface.

10 The plastic shelves formed by the sheets or plates 1 and 2 substantially fit around the face of the individual and extend just below the chin of the individual. On the inner side of this face there is a ring 4' of material which may also be a plastic material. This ring it will be noted from the figures extends substantially around the periphery of the mask from one side of the cannister 5 to the other side of the cannister to a place adjacent the outer edge of the breathing chamber 6 for the inhalation of air by the individual when the mask is in position.

15 As will be seen more particularly from Figure 3 bordering the ring 4 is a sealing ring 7 which is affixed by cement or otherwise to the face of the ring 4' and which also extends completely around the edge of the mask from the outside of the chamber 6 on one side of the outside of the chamber on the other side. In fact this sealing ring 7 which is of soft rubber extends to the sides of another ring 8 which is the sealing ring for 20 the chamber 6. This ring 8 goes slightly under the chin around the mouth and over the nose approximately at the bridge of the nose forming a sealing element for the chamber 6 so that all the air which is breathed by the individual into 25 the mask will be breathed through the cannister 5. Air enters the chamber formed with the face as one side and the inner wall 2 of the mask as the other side through a series of holes 9 passing through the flange or section 41 around the edge 30 of the mask. These holes are substantially uniformly spaced around the whole mask so that the air enters through them substantially uniformly into the inner chamber formed between the face of the inner wall and the mask. However these 35 holes are sufficiently small so that there is very little movement of air in the chamber against the face in and out of the mask and this permits the air in this chamber to attain a comfortable temperature which the face can endure even 40 holes are sufficiently small so that there is very little movement of air in the chamber against the face in and out of the mask and this permits the air in this chamber to attain a comfortable temperature which the face can endure even 45 through the air outside the mask may be very low. It has been found that the temperature inside the mask is bearable even though the temperature outside the mask may drop as low as 50 60° F. or 70° F. below zero.

55 The cannister 5 may also be made of plastic

3

material and comprises a front face 10 which preferably is not perforated and a rear face 11 which is perforated as indicated by the holes 12, Figure 1. This cannister may be formed as an integral element or may be built up with the face 10, the rear face 11 and the end plates 13 and 14 as individual elements formed together. The cannister is joined to the mask at the bottom just below or in the region of the chin and a sealing ring 8 of soft rubber or other suitable material similar to the sealing ring 7 is sealed or attached to the face of the cannister as shown at 15 and around at the sides of the cannister as indicated more clearly in Figure 1.

It will also be noted in the construction in the figures that the wall 10 of the cannister continues upward in the section 16 within the mask and forms a partial frame against which the ring 8 rests, except across the top where a section of the wall 16 is cut out to permit the ring 8 to lie over the bridge of the nose, effecting a complete seal for the nose and mouth by means of the ring 8. Air which goes up through the cannister therefore only comes to the nose and mouth of the wearer and does not enter into the chamber between the face and the inside wall of the mask. This prevents moisture which is in the breath from coming into the face chamber. Air entering into the cannister enters partly through the perforations 12 and also through the end piece 17 which may be detachable from the bottom of the cannister by being snapped over a bead at the end of the cannister as indicated at 18 so that the lower end of the cannister may be removed for replacement of another piece.

The piece 17 is a baffle with a baffle plate 19 just above the opening 20 in the piece. Air will be drawn in through the opening 20 around the baffle and up through the holes 21 in the baffle plate 22. The section of the baffle above the baffle plate 22 may be filled with glass wool or other material to govern the rate of flow with which the air is drawn into the mask when used by an individual.

The mask may be attached to the face by a series of straps 23 and 24 which may have their ends secured to places in the hard ring or flange 4' by means of a series of clips 25 which may be provided with slots through which the straps attach.

It will be noted from the above description that the whole chamber which extends around the nose and the mouth is not completely enclosed by the wall of the face mask. The yielding, soft, non-deformable sealing members 7 and 8 are therefore substantially on the same level where they join one another, and the lower portion of the sealing member 8 as will be noted from Figures 1, 3 and 4, extends considerably below the periphery of the face mask. Air which enters into the chamber 6 in the region of the nose and mouth is not only substantially warmed by the surrounding chamber adjacent the face, but also is closed on the outward side so that the air is to some extent retarded since it is drawn upwards through the mask away from any regions where strong blasts of cold air could blow through the lower conduit or cannister.

The warm air which is exhaled from the individual, diffuses with the cold air coming upwards through the bottom, and while it might first seem that the carbon-dioxide from the breath might not be carried away, nevertheless it is, through diffusion and because carbon dioxide is heavier than air, it gradually is carried off from the lower

end of the cannister and permits normal breathing of the individual of comfortable conditioned air.

Having now described our invention, we claim:

1. A face mask comprising a transparent plastic continuous wall formed to extend around the front and side of the face of an individual from a position in the normal region of the forehead in front of the ears and around the chin covering substantially the whole face of the individual, said wall being formed of two parallel spaced plastic sheet elements with a sealing flange around the periphery of the elements, a second flange element lying against the periphery of said wall inwardly thereof in the direction of the individual's face, said second flange being of substantially hard material and having a series of spaced holes extending through the material of the flange adjacent the inside periphery of the wall, a third flange member of soft yielding non-permanently deformable material applied around the periphery of said second flange acting as a seal for the mask against the face, means forming a separate chamber at the lower end of the mask for the nose and mouth, said means comprising a second wall element having portions joined to said first wall in the lower sections thereof and a portion extending continuously in front of and at the sides of the nose and mouth, a nose and mouth sealing flange of soft yielding non-permanently deformable material applied continuously around the edge of the second wall in the portion which extends around the nose and mouth, the means forming said separate chamber having a downwardly extending air conduit having opening in the direction towards the body of the individual when the mask is in place and means for attaching the mask to the head of the individual.
2. An arrangement as set forth in claim 1, in which there is a partial vacuum between the two parallel spaced sheet sections forming the wall of the mask.
3. An arrangement as set forth in claim 1 in which the means forming a separate chamber having a downwardly extending air conduit has an opening at the end of the conduit with a baffle element across the same.
4. An arrangement as set forth in claim 1 in which the means forming a separate chamber having a downwardly extending air conduit terminates in an open end and means removably attachable to such end providing a series of baffles for the circulation of air into and out of said chamber.
5. An arrangement as set forth in claim 1, in which said means forming a separate chamber for the nose and mouth has a section extending outside of the wall of the face mask.
6. A face mask comprising a transparent plastic continuous wall formed to extend around the front and side of the face of an individual from a position in the normal region of the forehead in front of the ears and around the chin, covering substantially the whole face of the individual, said wall being formed of two parallel spaced plastic sheet elements with a sealing flange around the periphery of the elements, a second flange element lying against the periphery of said wall inwardly thereof in the direction of the individual's face, said second flange being of substantially hard material and having a series of spaced holes extending through the material of the flange adjacent the inside periphery of the wall, a third flange member of soft yield-

ing, non-permanently deformable material applied around the periphery of said second flange acting as a seal for the mask against the face, means forming a separate chamber at the lower end of the mask for the nose and mouth, having a sealing ring around the periphery of the chamber adapted to fit around the nose and mouth of the individual sealing the chamber from the rest of the mask, and an air conduit directly connected to said separate chamber only 10

whereby said mask and separate chamber are sealed off effectively from one another.
